UNITED STATES PATENT OFFICE.

STANLEY H. HOBSON, OF ROCKFORD, ILLINOIS, ASSIGNOR TO GEO. D. ROPER CORPORATION, OF ROCKFORD, ILLINOIS, A CORPORATION OF ILLINOIS.

DESIGN FOR A COMBINED GAS STOVE AND RANGE.

Application filed February 4, 1927. Serial No. 20,618. Term of patent 14 years.

To all whom it may concern:

Be it known that I, STANLEY H. HOBSON, a citizen of the United States, residing at Rockford, in the county of Winnebago and State of Illinois, have invented a new, original, and ornamental Design for a Combined Gas Stove and Range, of which the following is a specification, reference being had to the accompanying drawing, forming part thereof.

In the drawing—

The figure is a perspective view of a combined gas stove and range, showing my new design.

I claim:

The ornamental design for a combined gas stove and range, as shown.

STANLEY H. HOBSON.
